Communication dated Jan. 31, 2019 from the Japanese Patent Office in application No. 2018-010480.

Primary Examiner — T Chase Nelson*Assistant Examiner* — Mary Claire Ramirez(74) *Attorney, Agent, or Firm* — Sughrue Mion, PLLC(57) **CLAIM**

The ornamental design for a digital camera, as shown and described.

DESCRIPTION

FIG. 1 is a front-left perspective view of a digital camera showing my new design;

FIG. 2 is a front-right perspective view thereof;

FIG. 3 is a rear-right perspective view thereof;

FIG. 4 is a rear-left perspective view thereof;

FIG. 5 is a front view thereof;

FIG. 6 is a rear view thereof;

FIG. 7 is a top plan view thereof;

FIG. 8 is a bottom plan view thereof;

FIG. 9 is a right side view thereof; and,

FIG. 10 is a left side view thereof.

The dashed broken lines depict portions of the digital camera that form no part of the claimed design. The long and short dashed lines indicate the boundaries of the claimed design and form no part of the claimed design.
